UNITED STATES PATENT OFFICE.

PHILIP F. CORBETT, OF BOSTON, MASSACHUSETTS.

CLAMP.

SPECIFICATION forming part of Letters Patent No. 376,637, dated January 17, 1888.

Application filed April 16, 1887. Serial No. 235,004. (No model.)

To all whom it may concern:

Be it known that I, PHILIP F. CORBETT, of Boston, in the county of Suffolk, State of Massachusetts, have invented a certain new and useful Improvement in Clamps, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved clamp; Fig. 2, a top plan view of the same; Fig. 3, an enlarged side elevation of the tail-stock detached; Fig. 4, a top plan view of the same; Fig. 5, a vertical transverse section taken on line *x x* in Fig. 3; and Fig. 6, a vertical longitudinal central section through a portion of the tail-stocks and body, showing the construction of the teeth or dogs on the tail-stocks and the sockets therefor in the body.

Like letters of reference indicate corresponding parts in the different figures of the drawings.

My present invention relates to that class of clamps which are employed by carpenters, cabinet-makers, and other wood-workers for gluing up their work, and is designed as an improvement on the clamp secured to me by Letters Patent of the United States No. 292,207, dated January 22, A. D. 1884; and it consists in a novel construction and arrangement of parts, as hereinafter fully set forth and claimed, the object being to overcome certain minor defects in said patented clamp and produce a more effective device of this character than is now in ordinary use.

The nature and operation of the improvement will be readily understood by all conversant with such matters from the following explanation.

In the drawings, A represents the body of the clamp, B the head-stock, and C the tail-stock.

The body is provided with a metallic cap-plate, D, which is secured thereto by screws *f*, and beneath the projecting edges of said plate, at either side thereof, the body is rabbed to form the grooves *t t*, as best seen in Fig. 5.

The tail-stock C is preferably composed of metal, and is provided at its rear or outer end

with a downwardly-projecting flange, *k*, at either side of the body A. A pin or stud, *i*, is rigidly secured in each of the flanges *k*, said pins respectively projecting into the grooves *t* in the body A, in which they are fitted to slide, and keeping the rear or outer end of the tail-stock in proper position when the clamp is in use.

Centrally pivoted at *m* to either side of the tail-stock C, near its inner or forward end, there is a downwardly-projecting vertically-arranged lever, E, provided on its inner face, near the lower end, with a hook or catch, *r*, adapted to enter the groove *t* beneath the plate D, as best shown in Fig. 5. A coiled spring, *y*, is disposed around each of the pivots *m*, one end of which rests against the upper end of the lever E, as shown at *g*, and the other against the body of the tail-stock, as shown at *b*, said spring acting expansively to force the upper ends of said levers outward and to keep the catches *r* in the grooves *t* or in engagement with the edges of the plate D. A series of centrally-arranged backwardly-inclined sockets, *d*, are formed in the plate D and top of the body A; and, projecting downward from the under side of the tail-stock C, near its inner or forward end, there is a backwardly-inclined hook or dog, *v*, adapted to enter said sockets and anchor or secure the tail-stock when the clamp is in use.

As the head-stock B is constructed in substantially the same manner as the tail-stock, excepting as hereinafter specified, it is not deemed essential to describe it fully.

A horizontally-arranged screw, H, is mounted centrally on the head-stock B, said screw being fitted to work in correspondingly-threaded holes (not shown) in the inwardly-projecting portions or flanges *l*, and provided at its inner or forward end with a guard, *w*, and at its rear or outer end with a handle, *z*.

A hook or dog, *v*, projects downwardly from the under side of the head-stock B near its inner or forward end, said hook being adapted to enter a socket, *d*, formed in the plate D and body A, as shown in Fig. 1, and anchor or secure the head-stock in substantially the same manner that the hook *v* anchors or secures the tail-stock, it being understood that the hook on the head-stock and also the socket in which it enters are respectively inclined in a direc-

tion opposite the hook on the tail-stock and sockets for receiving said last-named hook.

A slide, *J*, is mounted on the plate *D* between the head and tail stocks, said slide being provided with an angular flange at either side near the bottom, which projects into the groove *t* and keeps the slide in position on the plate. The slide is also fitted with a vertically-arranged set-screw, *j*, provided at its lower or inner end with a guard, 20, which presses on the plate *D* when the screw is turned in, and thereby anchors the slide or prevents it from slipping when in use.

In the use of said patented clamp, when the head and tail stocks are in position and the body is turned upside down, as is frequently necessary in gluing up cabinet and similar light work, the hooks at the inner ends of said stocks are liable to fall out of their sockets unless the work is firmly clamped and there is a strain on the screw, thereby frequently causing injury to the work and rendering it necessary to reverse the position of the body and adjust the stocks before the clamp can be used. It also sometimes occurs that the body of the clamp has to be turned upside down to insert the work; and in such instances, there being no strain on the screw, the hooks at the inner ends of the stocks are liable to drop from their sockets, thus necessitating readjusting the clamps and causing a loss of time and labor. My present invention is designed to obviate this objection; and to that end I make use of the spring-actuated levers *E*, provided with hooks or catches *r*, whereby the inner or forward ends of the stocks are prevented from falling away from the plate *D* and withdrawing their hooks *r* from their respective sockets *d* when the body *A* is turned upside down. In the use of the clamp, when it is desired to withdraw the hook of either stock from its socket, the upper ends of the levers *E* are pushed inward, thereby disengaging the catches *r* and projecting edges of the plate *D*, and permitting the hook to be readily withdrawn from its socket, in a manner which will be readily obvious without a more explicit description.

The guard 20 on the set-screw *j* is considerably greater in diameter than the lower end of said screw, which is fitted to turn therein, but not to be withdrawn therefrom; and by presenting a large bearing-surface said guard prevents the slide *J* from slipping as readily on the plate *D*, when the screw is turned in to secure it in any desired position, as would otherwise be the case.

In the use of my improved clamp the work is placed between the tail-stock *C* and slide *J*, after which the screw *H* is turned in against

said slide, forcing it against the work, the screw *j* being turned in or down to secure the slide in position when sufficient pressure has been exerted on the work by the screw *H*, after which the head-stock may be removed, 65 if desired, leaving the work clamped between the tail-stock and slide, thus enabling the same head-stock to be used with several bodies.

The stocks are respectively rounded on the under side at their rear or outer ends, as shown by dotted lines at 42, to enable the stocks to be readily tilted or thrown back in detaching the hooks from the sockets.

I do not confine myself to the use of two of the levers *E* with each stock, as one may be 75 employed, although I deem two much preferable. Neither do I confine myself to using the slide *J*, as this may be omitted, if desired, and the work clamped directly between the stocks; nor to the use of the plate *D*, as this 80 may be omitted and the sockets *d* and grooves *t* formed directly in the body *A*; nor to constructing the body *A*, stocks *B C*, screw *H*, or slide *J* of any special materials, as any suitable materials may be used; nor to the use 85 of the studs *i*, as these may be omitted, if desired, although their use is preferable.

Having thus explained my invention, what I claim is—

1. In a clamp of the character described, 90 the tail-stock *C*, provided with the dog or hook *v*, and pivoted spring-actuated lever *E*, having the catch *r*, in combination with the body *A*, provided with the socket *d* and groove *t*, substantially as described. 95

2. In a clamp of the character described, the tail-stock *C*, provided with the hook *v*, studs *i*, and pivoted spring-actuated lever *E*, having the catch *r*, in combination with the body *A*, provided with the socket *d* and groove 100 *t*, substantially as set forth.

3. In a clamp of the character described, the tail-stock *C*, provided with the hook *v*, and pivoted levers *E*, having catches *r*, in combination with the body *A*, provided with the 105 socket *v* and grooves *t t*, said levers being respectively arranged on opposite sides of said stock, and provided with springs adapted to force their catches into said grooves, substantially as shown and described. 110

4. In a clamp of the character described, the head-stock *B*, provided with the hook *v*, studs *i*, and spring-actuated levers *E*, having the catches *r*, in combination with the screw *H* and body *A*, provided with the socket *d* 115 and grooves *t t*, substantially as set forth.

PHILIP F. CORBETT.
